Inventor
Ernest Gregory,

By *George E. Hale*
Attorney

UNITED STATES PATENT OFFICE.

ERNEST GREGORY, OF NEW HAVEN, CONNECTICUT, ASSIGNOR TO THE LYONS MANUFACTURING COMPANY, OF HAMDEN, CONNECTICUT, A CORPORATION OF CONNECTICUT.

CIGARETTE CASE.

Application filed May 12, 1927. Serial No. 190,848.

This invention relates to improvements in cigarette cases, and particularly to the ejecting mechanism thereof.

It is the object of this invention, among other things, to provide in connection with a cigarette case, a simple and effective device, whereby the cigarettes may be manually and successively ejected therefrom; other features being the provision of means to minimize the friction between the parts, the possibility of damaging the paper of the cigarettes, insuring the ejection of the last cigarette in the case with the same facility as those preceding it, and in these and other ways to produce a cigarette case that will have none of the many objectionable features of the cigarette cases heretofore made, and at the same time be highly efficient in its operation.

20 The improvements in the details and arrangement of parts will be apparent from an inspection of the accompanying drawings in connection with the description herein-after contained, and wherein a preferred embodiment of the invention is disclosed for the purpose of imparting an understanding of the same.

In the drawings:—

Figure 1 is a fragmentary plan view of a cigarette case embodying my new improvements;

Figure 2 is a transverse sectional view the parts in section being taken generally upon line 2—2 of Figure 1;

35 Figure 3 is a fragmentary sectional plan view of the cigarette case, the parts in section being taken generally upon line 3—3 of Figure 2; and

Figure 4 is a fragmentary sectional detail 40 of the parts, taken upon line 4—4 of Figure 2.

Having more particular reference to the drawings, and in connection with which like characters indicate corresponding parts in the several figures; 10 represents the body of the cigarette case; 11 the cover thereof which is slidably connected with the body; 12 the follower which is normally in contact with one of the cigarettes in the body and 50 is moved forward by the spring 13; and 14 is the strap which holds the cigarettes against accidental outward displacement when the cover 11 is open.

The mechanism just described is old in

the art and constitutes no part of my present invention.

Through one of the side walls of the body, adjacent to the end wall 16, is the discharge opening 15, and in the wall opposite thereto is an opening 17 for a purpose hereinafter described.

Integral with the end wall 16 is a lug 18, which is formed by turning a portion of the wall outwardly and adjacent thereto is a slot 19.

Within the body, and adjacent to the end wall 16, is an ejector 20, having a side wall 21, which terminates at one end in the finger 22 and between its ends is a foot portion 23 which projects inwardly and away from the wall 16. The side wall 21 is formed with an offset portion 24 near the finger 22 and another offset portion 25 adjacent to the opposite end thereof. The top of each of these offset portions contacts with the inner face of the wall 16, the only engagement therebetween. By thus minimizing the extent of the contact between the ejector and the end wall, a freer, easier moving ejector results and the possibility of any loose fragments of tobacco or paper getting in between the ejector and end wall and thus jamming the mechanism and preventing its easy operation is entirely eliminated. These offset portions also position the finger 22 so that it will pass through the opening 17, no portion of which is in the end wall 16. This has several advantages, in that, from the view of the manufacturer, the difficulty and expense of cutting an opening through the walls of the body at the corners thereof is eliminated, and secondly, the finger 22 is not exposed through the end wall, thus avoiding what might otherwise, and is in some cigarette cases, an unsightly element.

The foot portion 23 projects under the cigarette in the body and thus forms a support therefor. This is an additional support over that ordinarily provided against one side only. With such support, the cigarette is lifted slightly from the bottom of the body and thus does not slide over the surface thereof with the possible chance of being torn or otherwise damaged, as frequently happens where the cigarette during the process of ejection is in contact with a fixed part of the body.

Adjacent to the end wall 16, upon the outer face thereof is a pressure case 26, which is substantially U-shape in cross section, with two walls thereof, between its ends, for a limited distance turned inwardly at 27, which then pass through the slot 19 and terminate in the wing portions 28, which project outwardly and rest within the offset portion 25. The length of these wing portions is substantially the same as that of the offset portion 25, so that there is no relative movement therebetween. The depth of the offset portion 25 is either exactly that of the thickness of the wing portions 28, or slightly greater. As so constructed, there is no part projecting beyond the inner face of the ejector 20, which thereby presents a straight, smooth surface against which the cigarette contacts.

20 Within this case 26 is a coil spring 31, between the lug 18 and an end wall. When at rest the parts are in the position substantially as shown in Figure 3, with the finger 22 in the opening 17 and substantially flush with the outside wall thereof, this position being determined by the engagement of the end of the wing portions 28 with the end of the slot 19.

In the drawings, I have illustrated by dotted lines, in Figure 1, two cigarettes, one adjacent to the follower being designated 29 and the one adjacent to the ejector, 30.

The cigarette 30 is held against the wall 21 of the ejector by the spring 13 and the underside thereof rests upon the foot portion 23. To eject this cigarette, pressure is applied by the finger to the pressure case 26. This moves the ejector parallel to the end wall, the finger 22 engaging the end of the cigarette and projecting the same through the opening 15 where it is engaged by the fingers and withdrawn. As soon as the pressure is released from the pressure case the spring 31 returns the ejector to the position shown in Figure 3 ready for the next succeeding cigarette and the follower 12 moves the next cigarette 29 in the column against the ejector mechanism and the operations are repeated as before.

50 The ejector mechanism of this cigarette case is comparatively simple in its structure, avoids the necessity of use of parallel and spaced end walls as is common in mechanisms of this character, and the possibility of the device becoming inoperative by the pieces of tobacco and paper becoming lodged between the moving parts is entirely eliminated. The cigarette also is so supported that it is not dragged over a fixed part while being ejected.

There are minor changes and alterations that may be made within my invention and I would therefore have it understood that I do not limit myself to the exact construction herein shown and described, but claim

all that falls fairly within the spirit and scope of the appended claims.

What I claim as new and desire to secure by Letters Patent, is:—

1. In a cigarette case, a body having a discharge opening in one wall thereof; a second opening in the opposite wall; a cover movable on the body; a follower to move the cigarettes toward one wall of the body; an ejector within the body movably connected with the last mentioned wall, and in the path of the cigarettes as moved by the follower, said ejector comprising a member having a side wall, provided with a plurality of offset portions, the top of each of which engages the adjacent wall of the body, a foot portion that projects from said side wall under a cigarette in contact with the side wall, and a finger at one end of the side wall that projects into said second opening and turned inwardly from the side wall; a pressure case connected with the ejector but upon the opposite side of the wall; and a spring for moving the pressure case in one direction.

2. An ejector for a cigarette case, having a side wall that terminates at one end in a finger with a plurality of offset portions upon one side thereof, and a foot portion that projects laterally from the bottom of the side wall in a direction opposite to the offset portions.

3. An ejector for a cigarette case, having a side wall that terminates at one end in a finger with a plurality of offset portions upon one side thereof, and a foot portion shorter than the side wall that projects laterally from the bottom of the side wall in a direction opposite to the offset portions.

4. In combination with a cigarette case having one wall with a slot therethrough; an ejector mechanism, comprising an ejector plate having a side wall that terminates at one end in a finger and a plurality of offset portions at one side thereof, and a foot portion that projects laterally from the bottom of the side wall in a direction opposite to the offset portions, a pressure case upon that side of the wall opposite to the ejector plate having inwardly turned portions that project through the said slot and terminate in wing portions within one of said offset portions; and a spring within the pressure case having contact at one end with a portion of said wall.

5. In combination with a cigarette case having one wall with a slot therethrough; a lug formed thereon by turning a portion of the wall at an angle to the wall; an ejector mechanism, comprising an ejector plate having a side wall that terminates at one end in a finger and a plurality of offset portions at one side thereof, and a foot portion that projects laterally from the bottom of the side wall in a direction opposite to the off-

set portions, a pressure case upon that side of the wall opposite to the ejector plate having inwardly turned portions that project through the said slot and terminate in 5 wing portions within one of said offset portions, said pressure case at all times covering said slot and the opening in the wall from which the material was taken to form

10 said lug; and a spring within the pressure case having contact at one end with a portion of said wall and at the other end with the said lug.

In testimony whereof, I have hereunto affixed my signature.

ERNEST GREGORY.
